UNITED STATES PATENT OFFICE.

GEORGE W. McNEIL AND CLOYD F. ANDERSON, OF DENVER, COLORADO.

HYDRAULIC CARTRIDGE.

1,358,767.

Specification of Letters Patent. Patented Nov. 16, 1920.

Application filed June 7, 1919, Serial No. 302,384. Renewed September 20, 1920. Serial No. 411,559.

To all whom it may concern:

Be it known that we, GEORGE W. McNEIL and CLOYD F. ANDERSON, citizens of the United States, residing at Denver, in the county of Denver and State of Colorado, have invented certain new and useful Improvements in Hydraulic Cartridges, of which the following is a specification, reference being had to the accompanying drawings.

This invention relates to certain improvements in hydraulic cartridges and has relation more particularly to a device of this general character especially designed and adapted for use in the breaking down of coal or other material, and it is an object of the invention to provide a novel and improved device of this general character embodying a plurality of pistons operating in individual cylinders and wherein each of said cylinders has in communication therewith a duct independent of the remainder of the cylinders and leading from a source of fluid pressure.

An additional object of the invention is to provide a device of this general character including pistons outwardly movable under fluid pressure and wherein novel and improved means are included for automatically regulating the outward movement of the pistons, together with means whereby the pistons move inwardly by suction or through the creation of a vacuum.

A further object of the invention is to provide a cartridge of this general character wherein the operating means therefor includes a pressure chamber and a fluid reservoir in communication therewith, together with means arranged within the reservoir and operated exteriorly thereof for creating the requisite pressure within the pressure chamber.

Furthermore, it is an object of the invention to provide a device of this general character wherein the requisite pressure is created through the instrumentality of a single operating member, together with means coöoperating with the operating member for releasing the pressure.

A still further object of the invention is

to provide a novel and improved cartridge of this character wherein the pistons are angularly arranged with respect to the longitudinal axis of the body of the cartridge, whereby the device is particularly adapted for use in connection with an upwardly inclined bore and which character of bore can be drilled with greater convenience and facility than a horizontal bore.

It is also an object of the invention to provide a novel and improved device of this general character including a plurality of pistons wherein each of the pistons is placed under pressure independently of the remainder, so that a leak in one or more of the cylinders for the pistons does not affect the others and wherein all of the pistons move uniformly and simultaneously regardless of varying outward conditions and particularly as offered by the variance in the load or resistance offered separately to the pistons.

The invention consists in the details of construction and in the combination and arrangement of the several parts of our improved hydraulic cartridge whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a somewhat diagrammatic view illustrating a hydraulic cartridge constructed in accordance with an embodiment of our invention and in applied position.

Fig. 2 is a longitudinal sectional view, with portions broken away, of a hydraulic cartridge constructed in accordance with an embodiment of our invention.

Fig. 3 is an enlarged fragmentary view of the working face of the body of the cartridge as herein embodied.

Fig. 4 is a transverse sectional view taken through Fig. 1 with the piston in elevation.

Fig. 5 is an enlarged fragmentary view illustrating in detail the pressure chamber and the parts concomitant thereto.

Fig. 6 is a sectional view taken substantially on the line 6—6 of Fig. 5.

Fig. 7 is a view in bottom plan of the device as herein embodied, with portions broken away.

Fig. 8 is a view in elevation of the outer 10 face of the pressure piston as herein included, and

Fig. 9 is an enlarged fragmentary sectional view taken longitudinally of one of the pump cylinders with a plunger arranged therein.

As disclosed in the accompanying drawings, B denotes the body of the cartridge which is substantially cylindrical in form but having a flat face 1 extending the entire 20 length thereof. The body B is of such dimensions as to be readily inserted in a hole or bore a drilled in coal or other material to be broken down or displaced and which hole or bore is positioned a desired distance above 25 the mining or kerf b (Fig. 1).

The flat face 1 has produced therein a plurality of pockets or cylinders 2 spaced longitudinally of the body. The axial centers of the pockets or cylinders 2 are arranged in parallelism and on a slight angle relative to the longitudinal axis of the body B and inclined in a direction toward the inner end of said body.

Working in each of the pockets or cylinders 2 is a piston 3. The inner end portion of the piston has secured thereto a cup gasket 4 or the like for contact with the inner wall of the pocket or cylinder 2 for a purpose which is believed to be apparent.

The inner end portion of the body B has secured thereto an end portion of a hollow member or pipe 5, the opposite end of which being secured to and extending through the axial center of a plate 6.

The body B is provided with a duct 7 for each of the pockets or cylinders 2 and which duct communicates with its pocket or cylinder at the inner end thereof. It is to be particularly noted that each of the ducts 7 is 50 free of the remainder and it is also to be noted that this is also true of the pockets or cylinders 2. Each of the ducts 7 is continued, as at 7^a, through the tubular member or pipe 5 and which continued portions 7^a 55 constitute piping.

The pistons 3 are adapted to be forced outwardly by fluid pressure, liquid or hydraulic, and by having the pockets or cylinders 2 for said pistons 3 angularly arranged, as hereinbefore recited, our improved cartridge is particularly adapted for use within a hole or bore a in the coal seam or other material which is disposed on an upward incline. The material advantage of this pro-

vision resides in the fact that it is much 65 easier to drill an upwardly inclined hole or bore a than if the same were drilled horizontally. By having the pistons moving in a path angular to the longitudinal axis of the body B, the line of pressure is in a correct direction or line of least resistance to effectively break the coal or other material and which is due to the fact that the line of pressure is not toward the solid coal or material behind the mining or kerf b.

In view of the particular mounting of the pistons 3, it is of importance to keep each of said pistons from turning in order to maintain a straight line along the outer ends or faces of the pistons. In order to accomplish 80 this result, each of the pistons 3 is provided in its side wall or periphery with a longitudinally disposed slot 8 into which extends an end portion of a clip 9 anchored to the flat face 1 of the body B.

C denotes an elongated hollow cylinder or body comprising two aligned sections X and Y having interposed therebetween, when assembled, a partition plate or septum 10, whereby the section X serves as a reservoir and the section Y constitutes a pressure chamber. The outer end of the section X is closed by a head 11 having its peripheral portion extended to afford an outstanding flange 12 while the outer end of the section Y is closed by a head 14. The head 14 is maintained in applied position by a plate 15 overlying the outer face of the head and extending beyond the periphery of said head. The flange 12 and the plate 15 are connected by the tie rods 16, whereby the sections X and Y and the interposed partition plate or septum 10 are maintained in assembled relation. The plate 6, hereinbefore referred to, is secured to the plate 15 90 through the instrumentality of the bolts 17.

The head 14 extends partially within the outer end portion of the section Y and has disposed therethrough a series of openings 18 of a number equal to the number of pockets or cylinders 2 in the body B. Fitting within each of the openings 18 is the forward end portion of a stationary tubular piston 19 and engaged within the forward end portion of the bore 20 of said piston is 110 a member or nut 21 which serves to maintain a piping 7^a in communication with the bore 20.

The inner end portion of the bore 20 of the piston 19 is enlarged as at 20^a and engaged within said enlarged portion 20^a is a tubular plug nut 22 which clamps to the inner end of the piston 19 a cup gasket 23.

P denotes a pressure cylinder mounted within the section Y inwardly of the pistons 19 and the forward face of said cylinder P is provided with the pockets or cylinders 24 with each of which coacts a piston 19. The

cup gasket 23 of each of the pistons 19 engages the wall of the pocket or cylinder 24 into which the piston 19 extends.

The cylinder P is moved forwardly by pressure in a manner to be hereinafter more particularly referred to and upon release of the pressure thereon, the cylinder P is moved rearwardly by the expansible members 25 herein disclosed as coil springs. A member 25 is arranged within each of the pockets or cylinders 24 and is interposed between the base of said pocket or cylinder and the internal shoulder 26 within the bore 20 of the coacting piston 19 and as afforded by the enlarged portion 20^a.

Arranged within the section X is a pair of pump cylinders 27. Each of the cylinders 27 has its forward end portion 27^a reduced and snugly disposed through an opening 28 in the partition plate or septum 10, and coacting with the outer extremity of said reduced portion 27^a and engaging the forward face of the partition plate or septum 10 is a clamping nut 29 which, in connection with the shoulder 30 as afforded by the reduced portion 27^a contacting with the inner face of the partition plate or septum 10, maintains the pump cylinder 27 in applied position.

The cylinders 27 discharge within the section or pressure chamber Y rearwardly of the cylinder P, and arranged within the discharge end portion of each of the cylinders 27 is a check valve 31 of a conventional type and whereby return flow into a cylinder 27 from the section or chamber Y is prevented.

Extending within each of the cylinders 27 from the rear is a plunger 32 having engaged with its forward end a cup gasket 33 for contact with the wall of the bore of the cylinder for obvious reasons. The outer extremity of the plunger 32 extends within a guide 34 secured to and extending outwardly from the head 11. The inner portion of the guide 34 is defined by an outstanding flange 35 contacting with the inner face of the head 11, and coacting with the outer face of the head 11 is a clamping nut 36 whereby the guide 34 is maintained in applied position. Also coacting with the plunger 32 exteriorly of its coacting cylinder 27 is a guide block 37 maintained in applied position through the medium of a screw 38 threaded through a wall of the section X and engaged within the block 37.

The plungers 32 are supported for rectilinear movement and travel simultaneously in reverse directions so that when one of the plungers is on its forcing stroke the second plunger is on a suction stroke.

Intersecting the section or reservoir X between the portion of the plungers 32 exteriorly of the cylinders 27 is a shaft 39 rotatably supported by the walls of said reservoir or section X and having an end portion 39^a extending exteriorly of the section or

reservoir X and with which extended portion 39^a is engaged an operating lever 40. The lever 40 is adapted to be swung manually.

Opposed faces of the plungers 32 exteriorly of the cylinders 27 are provided with the racks 41 meshing with a gear 42 suitably fixed to the shaft 39 so that as the lever 40 is recurrently swung or oscillated, the plungers 32 will be reciprocated.

Each of the cylinders 27 adjacent its forward end or at a point in advance of the coacting plunger 32 has in communication with the bore thereof a depending pipe 43 terminating in close proximity to the bottom or low portion of the reservoir or section X and interposed therein is a check valve 45 opening upon the suction stroke of the coacting plunger 32 but closing during the forcing stroke of said plunger.

In practice, the reservoir or section X is filled with a suitable liquid, preferably oil, and the pockets or pistons 24 in the pressure cylinder P, when in retracted position, together with the ducts 7, the piping 7^a, and the bores 20 of the pistons 19, are also filled with a similar fluid. When the cylinder P is in its retracted position, it is also to be understood that the cartridge pistons 3 are also retracted. As the operator recurrently swings or oscillates the lever 40, the resultant reciprocation of the plungers 32 forces the liquid from the reservoir or section X into the section or pressure chamber Y inwardly of the cylinder P and forces said piston outwardly. This outward movement of the cylinder P transmits pressure to the liquid within the pockets or cylinders 24, the bores 20, piping 7^a and ducts 7, causing the pistons 3 to move outwardly simultaneously and uniformly regardless of varying exterior conditions. In other words, if a ton weight were placed on any one of the pistons 3, all of the pistons will travel equally regardless of the fact that one of the pistons may have all the load to carry.

In order to facilitate the functioning of the cylinder P, a cup gasket 46 is secured to the rear face thereof for contact with the inner wall of the section or chamber Y.

The partition plate or septum 10 is also provided with an opening 47 in which is engaged an end portion of a sleeve 48 in communication with the section or pressure chamber Y. The sleeve has interposed therein a check valve 49 which is normally closed. Extending within the rear or inner end portion of the sleeve 48 is a stem 50 which, when moved inwardly, moves the valve 49 into open position. When the valve 49 is in open position, the pressure within the section or chamber Y is released and the cylinder P returns to its normal or retracted position under the influence of the expansible members or springs 25 hereinbe-

fore referred to. The returning movement of the cylinder P creates a suction which draws the liquid from within the pockets or cylinders 2 creating a vacuum inwardly of the pistons 3, whereby said pistons are caused to be retracted or moved inwardly.

In order that the desired inward movement of the stem 50 may be obtained when required, the shaft 39 is provided with an 10 outstanding lug 51 which, upon a full stroke of the lever 40, contacts with the outer end of the stem 50 and forces the same inwardly to move the valve 49 into open position.

In communication with the reservoir X 15 and the pressure chamber Y is a duct or pipe 52 and the communication of this duct or pipe 52 is normally closed by the cylinder P. As the cylinder P moves outwardly under pressure, the same passes over the point of 20 communication of the duct or pipe 52 with the chamber Y and when said point of communication is opened, the fluid under pressure returns through said duct or pipe 52 to the reservoir X and the outward movement of the cylinder P is stopped. It is, 25 therefore, to be understood that the extent of projection of the pistons 3 will depend upon the location of the point of communication between the duct or pipe 52 with the 30 reservoir Y relative to the partition plate or septum 10.

From the foregoing description, it is 35 thought to be obvious that a hydraulic cartridge constructed in accordance with our invention is particularly well adapted for use by reason of the convenience and facility with which it may be assembled and operated, and it will also be obvious that our invention is susceptible of some change 40 and modification without departing from the principles and spirit thereof and for this reason we do not wish to be understood as limiting ourselves to the precise arrangement and formation of the several parts herein shown in carrying out our invention 45 in practice except as hereinafter claimed.

We claim:

1. A hydraulic cartridge comprising a body provided in its face with a cylinder, 50 the axial center of the cylinder being inclined with respect to the longitudinal axis of the body, a piston mounted within the cylinder, and fluid means for forcing said piston outwardly.

55 2. A hydraulic cartridge comprising an elongated body comprising a plurality of longitudinally spaced cylinders, said cylinders having their axial centers angularly disposed with respect to the longitudinal axis of the body, said cylinders having their axial centers substantially in parallelism, pistons arranged within the cylinders, and fluid means for forcing said pistons outwardly.

60 3. A hydraulic cartridge comprising an elongated body comprising a plurality of

longitudinally spaced cylinders, said cylinders having their axial centers angularly disposed with respect to the longitudinal axis of the body, said cylinders having their axial centers substantially in parallelism, pistons 70 arranged within the cylinders, fluid means for forcing said pistons outwardly, and means for holding the cylinders against rotation.

4. A hydraulic cartridge comprising a 75 body provided with a plurality of cylinders, each of said cylinders being independently in communication with a separate source of fluid under pressure, and pistons within said cylinders. 80

5. A hydraulic cartridge comprising a body provided with a plurality of cylinders, each of said cylinders being independently in communication with a separate source of fluid under pressure, and pistons within said 85 cylinders, said cylinders being free one with respect to the remainder.

6. A hydraulic cartridge comprising a body provided in its face with a cylinder, the axial center of the cylinder being inclined with respect to the longitudinal axis of the body, a piston mounted within the cylinder, fluid means for forcing said cylinder outwardly, said piston being provided with a longitudinally disposed groove in a 90 side thereof, and a member carried by the body and extending within the groove of the piston for holding the piston against rotation.

7. A device of the character described 100 comprising a head with a plurality of cylinders, pistons working within said cylinders, and pressure means for forcing said pistons outwardly simultaneously and uniformly.

8. A device of the character described 105 comprising a head with a plurality of cylinders, pistons working within said cylinders, pressure means for forcing said pistons outwardly simultaneously and uniformly, and automatic means for limiting the extent of 110 outward movement of the pistons.

9. A hydraulic cartridge comprising, in combination, an elongated body provided with a plurality of cylinders, pistons working therein, a cylinder divided into a reservoir and pressure chamber, each of the cylinders of the body being separately in communication with its individual pressure pocket formed in the pressure cylinder, a pressure cylinder within the pressure chamber, and means for pumping a fluid within the reservoir into the pressure chamber to force the pressure cylinder outwardly 115 120

10. A hydraulic cartridge comprising, in combination, an elongated body provided with a plurality of cylinders, pistons working therein, a cylinder divided into a reservoir and pressure chamber, a pressure cylinder in the pressure chamber, and provided with pressure pockets, each of the cylinders 125 130

having a separate duct leading therefrom to an individual pressure pocket and adapted to contain a fluid, and means for pumping a fluid within the reservoir into the pressure chamber to force the pressure cylinder outwardly.

11. A hydraulic cartridge comprising, in combination, an elongated body provided with a plurality of cylinders, pistons working therein, a cylinder divided into a reservoir and pressure chamber, a pressure cylinder within the pressure chamber and provided with pressure pockets, each of the cylinders of the body being separately in communication with an individual pressure pocket, and means for pumping a fluid within the reservoir into the pressure chamber to force the pressure cylinder outwardly, said pressure chamber and reservoir having a return duct in communication therewith and normally closed by the pressure cylinder.

12. A hydraulic cartridge comprising, in combination, an elongated body provided with a plurality of cylinders, pistons working therein, a cylinder divided into a reservoir and pressure chamber, a pressure cylinder within the pressure chamber, and provided with pressure pockets, each of the cylinders of the body being separately in communication with an individual pressure pocket, means for pumping a fluid within the reservoir into the pressure chamber to force the pressure cylinder outwardly, means for relieving the pressure in the pressure chamber, and automatic means for returning the pressure cylinder upon release of the pressure upon said pressure cylinder.

13. A hydraulic cartridge comprising, in combination, a body provided with a cylinder, a piston movable within said cylinder, a pressure chamber, a reservoir to contain fluid, means for forcing the fluid from the reservoir into the pressure chamber, and a pressure cylinder within the pressure chamber operating by the fluid delivered within the pressure chamber, said pressure cylinder being in communication with the cylinder of the body, the means for forcing the fluid from the reservoir into the pressure chamber also including means for releasing the pressure in the pressure chamber.

14. A hydraulic cartridge comprising, in combination, a body provided with a cylinder, a piston movable within said cylinder, a pressure chamber, a reservoir to contain fluid, a pressure cylinder within the pressure chamber, said pressure cylinder being in communication with the cylinder of the body, a pump for forcing the fluid within the pressure chamber to move the pressure cylinder in one direction, means for operating the pump, a normally closed port in communication with the reservoir and the pressure

chamber, and means operated by the means for operating the pump for opening said normally closed port.

15. A hydraulic cartridge comprising, in combination, a body provided with a cylinder, a piston movable within said cylinder, a pressure chamber, a reservoir to contain fluid, a pressure cylinder within the pressure chamber, said pressure cylinder being in communication with the cylinder of the body, a pump for forcing the fluid within the pressure chamber to move the pressure cylinder in one direction, said pump being arranged within the reservoir, means for operating the pump, a normally closed port in communication with the reservoir and the pressure chamber, and means operated by the means for operating the pump for opening said normally closed port.

16. A hydraulic cartridge comprising, in combination, a body provided with a cylinder, a piston movable within said cylinder, a pressure chamber, a reservoir to contain fluid, a pressure cylinder within the pressure chamber, said pressure cylinder being in combination with the cylinder of the body, a pump for forcing the fluid within the pressure chamber to move the pressure cylinder in one direction, said pump being arranged within the reservoir and including a reciprocating plunger, a shaft intersecting the reservoir and engaged with the plunger for imparting endwise movement to the plunger, and means exteriorly of the reservoir for recurrently rotating the shaft.

17. A hydraulic cartridge comprising, in combination, a body provided with a cylinder, a piston movable within said cylinder, a pressure chamber, a reservoir to contain fluid, a pressure cylinder within the pressure chamber, said pressure cylinder being in communication with the cylinder of the body, a pump for forcing the fluid within the pressure chamber to move the pressure cylinder in one direction, said pump being arranged within the reservoir and including a reciprocating plunger, a shaft intersecting the reservoir and engaged with the plunger for imparting endwise movement to the plunger, means exteriorly of the reservoir for recurrently rotating the shaft, said reservoir and pressure chamber being in communication one with the other by a normally closed port, and means operable by the shaft for opening the port.

18. A device of the character described comprising a head with a plurality of cylinders, pistons working within said cylinders and pressure means for uniformly forcing said pistons outwardly.

19. A device of the character described comprising a body provided with a cylinder, the axial center of the cylinder being inclined with respect to the axis of the body, a

piston mounted within the cylinder, and means for forcing said piston outwardly.

20. A hydraulic cartridge comprising, in combination, a body provided with a cylinder, a piston working therewith, a cylinder divided into a reservoir and a pressure chamber, a pressure cylinder within the pressure chamber and in communication with the cylinder of the body, and means for pumping a fluid within the reservoir into the pressure chamber to force the pressure cylinder outwardly, said pressure chamber and

reservoir having a return duct in communication therewith and normally closed by the pressure cylinder.

15 In testimony whereof we hereunto affix our signatures in the presence of two witnesses.
